UNITED STATES PATENT OFFICE

147,413

DESIGN FOR A SHOE SOLE

Virgil M. Knisely, Lima, Ohio, assignor to Gro-Cord Rubber Company, Lima, Ohio, a corporation of Ohio

Application May 15, 1947, Serial No. 139,058

Term of patent 14 years

(Cl. D7—5)

To all whom it may concern:

Be it known that I, Virgil M. Knisely, a citizen of the United States, residing at Lima, in the county of Allen and State of Ohio, have invented a new, original, and ornamental Design for a Shoe Sole, of which the following is a specification, reference being had to the accompanying drawing, forming part thereof.

In the drawing:

Fig. 1 is a bottom plan view of a shoe sole, showing my new design;

Fig. 2 is an edge elevation as viewed from the right thereof; and

Fig. 3 is a section on the line 3—3 of Fig. 1.

I claim:

The ornamental design for a shoe sole, substantially as shown.

VIRGIL M. KNISELY.
